UNITED STATES PATENT OFFICE.

FRANKLIN GREAR NEAL, OF HALIFAX, NOVA SCOTIA, CANADA.

BOX-CAR.

1,187,921.

Specification of Letters Patent. Patented June 20, 1916.

Application filed November 15, 1912. Serial No. 731,596.

To all whom it may concern:

Be it known that I, FRANKLIN GREAR NEAL, a citizen of the United States of America, residing at Halifax, in the Province of Nova Scotia, Canada, have invented 5 certain new and useful Improvements in Box-Cars; and I do hereby declare that the following is a full, clear, and exact description of the same.

10 This invention has for an object to provide a car of this type having a body framework of superior strength and rigidity and to generally improve and simplify the detail construction thereof.

15 For further comprehension of the invention and of the objects and advantages thereof reference will be had to the following description and appended claims, and to the accompanying drawings forming part of 20 this specification in which similar reference characters indicate the same parts and wherein;

Figure 1 is a side elevation of one half of a box car constructed according to my invention: Fig. 2 is a horizontal section of the same half of the car: Fig. 3 is a side elevation of the other half of the car: Fig. 4 is a plan view thereof, part of the roof being removed to show the roof supporting framework: Fig. 5 is a transverse section of the car taken on the line 5—5 Fig. 4: Fig. 6 is an enlarged horizontal section of one corner of the car, the view being taken on the line 6—6 Fig. 1: Fig. 7 is a detail section on the line 7—7 Fig. 5 of the joint between the roof sections, the view being taken longitudinally of the car and transversely of the joint: Fig. 8 is a detail vertical section on the line 8—8 Fig. 7: Fig. 9 is a face view 40 of a portion of one of the side posts showing the manner of securing the side walls thereto: Fig. 10 is a vertical section on the line 10—10 Fig. 9: and Fig. 11 is a horizontal section on the line 11—11 Fig. 10.

45 My improved box car is provided with an all steel framework the understructure of which comprises a center sill 2 made up of a pair of longitudinal channel beams connected by suitable cross braces. Projecting 50 outwardly on opposite sides of the center sill are the cross arms or cross ties 4 which carry the side sills 5 on their outer ends, while the end sills which tie the ends of the center and side sills together are shown at 55 6, the end and side sills being braced by the gusset plates 7 and diagonals 8. These

cross arms have their upper faces downwardly inclined from the center and side sills toward points between the center and sides of the car to provide recesses adapted 60 to receive a pair of longitudinal Z-bars 9 which assist in supporting the floor of the car.

Supported upon the underframe above described is the superstructure of the car 65 comprising corner posts 10 of sheet metal of angular shape and having each flange reinforced by pressing the metal outward to present a vertical rib 10' running from top to bottom of the posts. These posts 70 overlap, and are secured at their lower ends to the adjacent ends of the end and side sills, their upper ends being similarly secured to the adjacent ends of the end and side plates, 11 and 12 respectively, which 75 support the roof. These plates 11 and 12 are formed of angle beams with their flanges turned outwardly from their top sides and are supported along the sides and ends of the car by intermediate posts 13 and 80 14 respectively, the side posts 13 being riveted at top and bottom to the side plates and side sills respectively while the end posts are riveted at their upper ends to the end plates and at their lower ends to the end sill 85 cover plates 15. The car sides are also braced by diagonals 16 which are riveted at top and bottom to the side plates and side sills respectively. These end posts, side 90 posts and diagonals are made of sheet metal pressed out to form central strengthening ribs 13', 14' and 16' as shown.

Secured at opposite ends to the side plates 12 are the roof bearers or carlines 20 which are formed of T-bars with downturned 95 flanges, the end portions of the flanges being cut-off and the foot bent down at the ends as shown at 21 and riveted to the side plates. These carlines are arched upwardly from 100 sides to center as shown and carry the roof which is of novel construction as will now be pointed out.

The roof of my improved car is divided longitudinally into a plurality of sheet metal sections 22 each extending the full width of 105 the car and between the carlines to which latter they are riveted by rivets 22', the adjacent sections being joined to one another by a special lock-joint formed by turning upwardly and slightly backwardly the edges 110 23 of the sections and slipping thereover cover-strips 24 having downwardly and in-

wardly projecting flanges 24 engaging the said edge portions 23, the ends of the cover strips being bent around under the outturned flanges of the side plates 12 as at 25 and rivets 26 are passed through these ends 25, the flanges of the side plates and the main body of the cover strips to hold the latter in position. The dove-tail arrangement of the upturned and downturned flanges 5 (which is clearly shown in Fig. 7 of the drawings) serves to lock the cover strips in position without any further attachments and provides a rain proof joint between the roof sections. As shown at 27 the edges of 10 the sheets 22 at the sides of the car are bent downwardly over the outturned flanges of the side plates 12.

The side walls 29 of the car are bolted to the side, end and corner posts and diagonals 20 and by making such posts of pressed sheet metal as before pointed out I am enabled to provide a simple means for securely locking the nuts 30 upon the bolts 31. This means is illustrated in detail in Figs. 9 and 10. As 25 shown in the drawings a series of tongues or slugs 32 are struck out of the metal of the posts. These tongues are bent outwardly as at 33 adjacent one side of each nut and then across the faces of the latter, the turned out 30 portions 33 preventing the nuts turning while the bolts are prevented from turning by the squared necks 31' on the bolts engaging the wood of the walls. As shown most 35 clearly in Fig. 10 the tongues 32 are of sufficient length to enable the portions 33 to be bent backward when desired away from the nuts and allow the latter to be turned.

What I claim is as follows:

1. A box car having corner posts of sheet

metal of angular cross-section, each of the 40 flanges of such posts being pressed outwardly, with respect to the car at a distance from their side edges to form a reinforcing rib.

2. A box car having corner posts of sheet 45 metal of angular cross-section, each of the flanges of such posts having a centrally located reinforcing rib pressed outwardly therefrom and with respect to the car.

3. A box car having a sheet metal corner 50 post consisting of a flange arranged on one side of the car adjacent one corner of the latter and having upon its exterior surface with relation to the car, an outwardly and longitudinally extending reinforcing rib spaced 55 from the longitudinal edges of such flange, and a second flange formed integrally with and disposed at an angle to the first flange, such second flange being arranged on an adjoining side of the car and having on its exterior surface with relation to the car, an outwardly and longitudinally extending reinforcing rib spaced from the longitudinal edges of said second flange.

4. In a box car, side walls, sheet metal wall 60 posts, bolts securing the said walls to the posts, nuts screwed on the bolts, the said sheet metal posts having tongues struck therefrom and engaging the said nuts to lock them in position.

In testimony whereof, I have signed my name to this specification, in the presence of two subscribing witnesses.

FRANKLIN GREAR NEAL.
